UNITED STATES PATENT OFFICE.

ELWOOD HEADLEY, OF NEW YORK, N. Y.

FARE-RECEIVER.

SPECIFICATION forming part of Letters Patent No. 336,410, dated February 16, 1886.

Application filed June 23, 1885. Serial No. 169,529. (No model.)

To all whom it may concern:

Be it known that I, ELWOOD HEADLEY, a citizen of the United States, and a resident of New York, in the county of New York and State of New York, have invented certain new and useful Improvements in Fare-receivers, of which the following is a specification, reference being had to the accompanying drawings, in which—

10 Figure 1 is a side elevation of the apparatus complete. Fig. 2 is a vertical section through the receiving-box and a portion of the tube. Fig. 3 is a vertical section of the receiving-box. Fig. 4 is a horizontal section of the same. Fig. 5 is a vertical longitudinal section of discharging-box. Fig. 6 is a horizontal section of the same. Fig. 7 is a vertical sectional view of the receiving apparatus and a portion of the tube through which the balls 20 are conveyed to the delivering-point. Fig. 8 is an enlarged sectional view of the tube M and valve N.

This invention has relation to a novel system and apparatus for receiving fares and detecting any irregularities in the receipt and disposition of the same.

As a feature of my fare-receiving and detecting system, I employ, instead of the usual ticket, slip, or coupon, which is usually no more than a representation of the fare paid, a device, preferably a small ball or globe of rubber, gutta-percha, or other suitable material, of about the intrinsic value of a fare. Such a device is a preventive of counterfeiting or stealing, for the reason that the cost of manufacture is so great that nothing can be gained by obtaining them from any but the proper source, and for the further reason that their bulk precludes the possibility of carrying sufficient on the person to repay the surreptitious act of stealing or otherwise unlawfully procuring the fare-balls. For use on elevated railways, ferries, and other places where the rate of fare varies, I propose employing 40 balls of different sizes and different values, thus adapting the balls to the same uses for which fare tickets or coupons are now employed.

The apparatus embodying my improvements is designed with special reference to the 50 employment of the balls; and it consists in the novel construction, combination, and arrange-

ment of devices, as hereinafter described, whereby provision is made for, first, allotting to each purchaser or payer of a fare a single ball for each fare paid; second, registering on 55 a dial or other indicator the sale of such fare; third, insuring the proper disposition or depositing of the balls in their receptacle; fourth, restoring the balls to their original position, so that the ticket-agent may use the stock 60 over and over again, and, fifth, in the provision of means supplementary to those already referred to, whereby any cheating, stealing, tampering with, or collusion in regard to fares is prevented or detected. 65

Essentially, my invention comprises a fare-receptacle corresponding in purpose with the fare-box ordinarily employed on elevated railways, or the like, a tube or tubes leading from the receptacle to the desk or office of the 70 cashier and terminating in a discharging apparatus, by means of which the balls are discharged in succession at the will of the cashier by operating a suitable valve, the discharge of each such ball being accurately registered 75 by means of a suitable device connected to the discharging-valve.

The tube or tubes above referred to are designed to contain the balls, and to provide for their security from appropriation by the 80 employés in charge.

In connection with the aforesaid tubes I propose to employ, and will presently describe in detail, devices for causing the accumulated balls to be transferred from the 85 receptacle in which they are deposited by the passenger to the discharging apparatus at the will of the gate-keeper.

Referring now to the special construction of the apparatus, A A' designate the tubes designed, respectively, for the accommodation of two sizes of balls, representing different values or fares. These tubes are identical in their construction and have the same appliances; hence a description of one tube will be sufficient. 90

Selecting the tube A for the purpose of description, said tube is of an inverted-U shape, with legs a a' of different lengths. The leg a, which is the shorter, rises from and is in direct communication with the discharging apparatus, while leg a' rises alongside of the re- 100

ceiving-box. The section or length A" uniting the two legs is slightly inclined downwardly from its point of curvature and connection with the leg a' to its similar point of connection with the leg a, in order that the balls, when lifted from the leg a' into the part A", will roll down toward and enter the leg a. The contents of the tube may at all times be observed through a longitudinal slit, b, cut in 5 any convenient portion of the tube, and formed in the leg a' and the inclined portion A". A series of indicating-points, b' b', suitably numbered, serve to indicate at a glance the contents of the slotted portion of the tube, 10 thereby avoiding the necessity of counting the balls.

The discharging-box, designated by letter C, consists of a suitable casing having in its front portion an aperture, c, through which 15 the balls are allowed to escape, one at a time, within reach of the passengers. Between this aperture and the end of the tube-leg a, which latter communicates with the interior of the box, is located a valve, d, consisting of a pivotal block having in its periphery a recess, d', adapted to receive a single ball. When this recess is turned upward, it coincides with the leg a of the tube, and admits therefrom a single ball only. When the valve is turned for- 20 ward, the ball is discharged through the aperture c, while the lower end of the leg a is closed, preventing the escape of other balls; hence it will be seen that but one ball can be discharged at a time, and only by a direct move- 25 ment of the valve. The valve is connected by means of a crank or eccentric, e, on its shaft, and a connecting-rod, e', with a permutating, registering, or indicating apparatus, E, having its dial exposed through an opening 30 in the side of the leg, by means of which registering or indicating apparatus a tally is made of each fare received and ball discharged, and a check therefore had upon the cashier's opera- 35 tions. The valve is actuated by the cashier through the medium of a valve-rod, f, within convenient reach of his hand, or connected to a treadle, f', which may for convenience be operated by his foot, so as to leave his hands free in making change or counting. 40 The discharging-box and registering apparatus are so placed as to be inaccessible to the cashier, while the discharge aperture is toward the front of his desk, within access of the passenger, but out of reach of the cashier. 45 G designates the receptacle into which the balls are dropped by the passengers as they pass through the gate. This receptacle corresponds in its general appearance to the ticket-box ordinarily employed on elevated 50 railways, and is formed with an opening, g, on top and with glass windows g' g', through which the interior of the box may be observed by the gate-keeper. Within the box G are placed two inclined racks, H H', which slant 55 from end to end downwardly toward the point where the balls leave the receptacle and later-

ally toward two similarly-slanting shelves, I I'. The racks H H' are formed with ribs h h', between which are slots h' h'. The slots in the upper rack are sufficiently large to permit the smaller-sized balls to fall therethrough onto the lower rack, H', while the larger balls roll down upon the shelf I, and thence into their proper tube, the smaller balls similarly passing to their proper tube along the shelf I. 70 75

To prevent the small balls from rolling on the ribs of the upper rack, I provide a device, Q, which consists of a transverse bar from which depend the fingers q q', of different lengths. The fingers q terminate above the 80 spaces between the ribs h a sufficient distance to allow the larger balls to pass thereunder, while the shorter fingers, q', terminate close to the ribs, and hence act as guards or fenders, which will arrest the passage of the smaller 85 balls and compel them to drop down onto the lower racks.

J designates a drawer, which is arranged below the racks H H', its purpose being to receive any article other than the balls before 90 referred to, which may be thrown into the receptacle, and which may be drawn out at any time for the removal of its contents without interfering with or delaying the depositing of the balls in their respective tubes. 95

k k designate rods placed across the receptacle and along the edges of the shelves I I', their purpose being to prevent the balls from rolling off sidewise from the shelves. Upon the shelves, and forming a part of the same, are 100 placed strips k' k', connected at one end to handles k' k' which project out through the sides of the receptacle G, alongside of the tubes A' A and within easy reach of the gate-keeper. By means of the handles k' k' these strips 105 may be reciprocated and the balls caused to fall into line and pass along the shelves to their respective tubes, thereby avoiding any jamming of the balls or obstructive accumulation of the same upon the shelves I I'. 110

The leg a' of the tube is provided with a piston, L, having a lateral stem, l, which projects through a slot, l', in said leg, and has connected to it a handle, l'', by means of which the piston is raised and lowered for the purpose hereinafter described. 115

At M is a sleeve or joint encircling the tube-leg a', and formed with an aperture, m, which constitutes the inlet for the balls from the receptacle G. Within the sleeve M is a tubular valve, N, having an opening, m', which, when the valve is in one position, coincides with the inlet m and allows the balls to enter the tube, while when the valve is turned to another position the wall of the latter closes said opening. Through a slot in the sleeve M a stem, o', which is connected to the valve, projects outward, and has a thumb-piece by which the valve may be manipulated. Above the valve M, and within the leg a', is 125 arranged a gravity-valve, p, which normally lies crosswise of the tube, preventing the balls 130

above it from falling down, while allowing those below to pass by freely.

In carrying my invention into practical use—say, for instance, on elevated railway-stations—

- 5 each cashier is allotted a given number of balls—say two hundred—which must be duly accounted for every evening to the proper officer or collector. These balls are placed in the tube by first dropping them in the receptacle.
- 10 Between the valve M and the bottom of the tube-leg a' there is space for, say, fifty balls, and when this leg is filled the piston L is lifted, causing the fifty balls to rise into the upper section of the leg a' . When the piston is
- 15 again raised, with a supply or load of balls, those in the upper part of the leg are displaced, and caused to be rolled over through the tube A into the short leg a' , when they are at the disposal of the cashier. Accordingly, it will
- 20 be seen, a given number of balls answer for all purposes of daily sale and operation, as they may be transferred from one leg of the tube to the other, according as required, thus keeping the cashier at all times supplied with sufficient
- 25 balls for the use of the passengers.

The register indicates every fare received; hence the cashier cannot steal fares, but must account for every one indicated by the register. Should a passenger fail to deposit his

30 fare-ball, an inspection of the tube will at any time indicate the loss and enable the company to take proper precautions against the im-
prop r use of the ball which the act may suggest.

35 If it should happen that a counterfeit ball is deposited, the fact can be detected the same day by the surplus contents of the tube, and means immediately employed to detect any further or wholesale use of counterfeit balls.

40 What I claim is—

1. In a fare-receiving device, the combination, with a delivering apparatus and tubes leading thereto, of a receptacle connected to said tubes and provided with slotted racks adapted and arranged so that balls of different sizes will be automatically separated and delivered to different tubes, substantially as described. 45

2. In a fare-receiving apparatus, the combination, with a tube for the reception of a series of balls, of a delivering and recording apparatus consisting of a pocket or valve adapted to discharge but one ball at a time, means, substantially as described, for operating the same, and a registering device operated by the movement of said pocket, substantially as set forth. 50

55 3. In a fare-receiving apparatus comprising arch-shaped tube or tubes for the reception of balls, the combination, with a delivery-box connected therewith, and a receptacle for the deposition of the balls, connected with said tubes, of a piston by the movement of which said balls are transferred from one section or leg of the tube to the other, substantially as described. 60

65 4. In a fare-receiving apparatus comprising arched tube or tubes for the reception of balls, having a piston in one end, by the movement of which the balls are shifted, the combination, with said tube, of a valve for closing 70 and opening the inlet from the receiving-box, and a valve to prevent the return of shifted balls, substantially as described.

Signed at New York, in the county of New York and State of New York, this 19th day of June, A. D. 1885.

ELWOOD HEADLEY.
